SNOWPLOW

Harvey W. De Vaux, Kansas City, Mo.

Application February 5, 1940, Serial No. 317,353

5 Claims. (Cl. 37—53)

This invention relates generally to snow removing implements in the nature of a manually operable plow, constructed to be moved forwardly by the operator and designed to have a number 5 of adjustable blades whereby the path cleared may be altered as to width, and further to permit the use of either one or more of the said blades by setting the structure forming a part of the equipment.

10 One of the important aims of this invention is the provision of a snowplow of the aforementioned character wherein is included a pair of blades mounted upon a specially formed body which has associated therewith, means for manually operating the plow and devices for securing the blades thereof at predetermined angles.

15 A yet further aim of this invention is to provide a snowplow of the type intended to be manually operated, which plow comprises a number 20 of collapsible parts, all of which may be manipulated to permit packing and storing of the plow without disassembling, and all of which cooperate to present a rigid, durable and rugged 25 implement when adjusted to the operative condition.

The foregoing broad objects as well as specific 30 aims will be exemplified to those skilled in the art by an understanding of the illustrated embodiment shown in the accompanying drawing, wherein:

Figure 1 is a top plan view of a snowplow made in accordance with the present invention.

Fig. 2 is a side elevational view of the same; and

Fig. 3 is a fragmentary detailed sectional view taken on line III—III of Fig. 1.

The principal supporting element of the snowplow is the planar body 6 which in practice, has been formed of a board or plank that extends 40 in a vertical plane on the longitudinal center line of the snowplow. To this body is attached a number of wheels 8, 10 and 12 respectively, so that the body may be moved along a supporting surface being cleaned upon wheels 8 and 10 and so 45 that when the plow is to be transported in an inoperative position, wheels 12 may be employed.

A specially formed blade 14 is hingedly mounted as at 16 to each side respectively of 50 body 6. This blade is of relatively heavy sheet metal and the marginal longitudinal edges thereof are bent laterally to present an arcuate overhanging portion which assists in scooping the snow from the surface being cleaned and 55 fines the snow to the outer surface of the blade

until it is deposited at the outermost free end thereof.

Blades 14 are attached to body 6 adjacent the forward end thereof and each blade has an associated wing 18 mounted on body 6 to insure that the snow will not pass behind the adjacent ends of blades 14.

The blades extend rearwardly and outwardly from each other and from body 6, and their angle of inclination, with respect to the body, may be predetermined and set through the employment of braces 20, one of which is disposed between each blade 14 and body 6. Each brace 20 has ears 22 at the ends thereof that are provided with openings for the reception of a pin 24, which when in the operative position, passes through bearings 26 mounted on the back side of blade 14.

The pivotal connection afforded by pin 24, ears 20 20 and bearings 26 allows the end of brace 20 adjacent to body 6, to be moved along the perforated fixtures 28 to a desired point. Ears 30 on the end of brace 20 near fixtures 28 have openings therethrough for the reception of a pin 32 and this pin is passed through ears 30 and the desired 25 perforation 34 of fixtures 28.

In the embodiment illustrated, fixtures 28 are in the form of angle irons secured to the side of body 6 and spaced apart as seen in Fig. 2. The 30 perforations 34 of these angle irons are in opposed relation and ears 30 rest upon these angle irons as shown.

A pair of handles 36 secured to the body at a point close to the forward end thereof, extend 35 upwardly, rearwardly and outwardly so as to afford the operator a convenient means for exerting the required forward force to operate the plow. Grips 38 on the upper rear ends of handles 36 are of the usual form and the distance 40 between these grips 38 is determined by a tie-rod 40, one end of which is pivotally secured to one of handles 36 as at 42. The other end of tie-rod 40 is removably engageable with a bracket 44 carried by the other handle 36 and an opening 45 46 intermediate the ends of tie-rod 40 is for the purpose of receiving a securing pin, hereinafter to be described.

While the rear and uppermost ends of handles 36 are so held apart by tie-rod 40, the forward 50 and lower ends are secured to body 6 through the medium of hinges 48, both of which are secured to body 6 by a pintle 50. This pintle permits the movement of handles 36 about a common center on the axis of the pintle and the hinges 55

allow movement of the handles toward and from each other.

Each handle 36 is supplied with a support comprising two links 52 and 54 respectively. The links are interconnected by a pin 56 and the ends are pivotally joined to handle 36 as at 58 and body 6 as at 60 so that folding may occur. A pin 62 is passed through the overlapped ends of links 52 and 54 to insure rigidity.

10 When the parts of the plow are in the position shown in full lines in Figs. 1 and 2, the same is ready for use. When the parts are folded to the position shown in dotted lines of said figures, the plow is ready for packing or storing.

15 A tongue 64 on the upper edge of body 6 has a hole 66 therethrough for the reception of a pin and when tie-rod 40 is in the position shown in dotted lines, hole 46 will be in register with hole 66 of tongue 64. In this position, links 52

20 and 54 are folded together and handles 36 are in a position on opposite sides respectively of body 6.

An exceptionally compact package is formed when the plow parts are folded together and a distinct advantage is gained, especially when implements of this character are used but a limited number of times through a given season of the year. Storage space is reduced to a minimum and when the plow is shipped by the manufacturer, the carton need not be heavy nor large.

30 It is obvious to one skilled in the art that the parts of the plow when in the operative position, will present a rigid structure without danger of collapse and having the ability to withstand any force that might be manually exerted in cleaning

35 a path. Because of the individual manner in which blades 14 are adjustably mounted, one blade may be drawn against body 6 while the other is used to clear a relatively narrow path. This is particularly advantageous when it is

40 necessary to clean the pavement close to a building. The hinges 48 permit the operator to draw handles 36 laterally a slight amount for the connection at 60 is free enough to allow the displacement—thus, the hand of the operator, next to 45 the building, will not engage the latter and speed and efficiency is gained.

The materials from which the plow is made insure a light-weight device and blades 14 are reversible so that when an edge, for example, becomes worn, the blades may be interchanged to present another longitudinal edge to the surface being cleaned. These blades 14 are likewise quickly renewable and the employment of a relatively flat, thin body 6 that is disposed on the 55 longitudinal center line of the plow, allows tipping to the desired extent to overcome obstacles that might be struck by the lower edge of either blade.

Obviously, plows having appearances different from that shown may be made without departing from the spirit of the invention or scope of the appended claims.

Having thus described the invention, what is claimed as new and desired to be secured by Letters Patent is:

65 1. A manually operable snowplow of the character described, comprising a flat, central body adapted to be disposed in a vertical plane when in the operative position; an outwardly and rearwardly extending blade hingedly joined to each side respectively of the body adjacent to the forward end thereof; means interconnecting each blade and the body at selected points along the length thereof adjacent to the other end of the body for holding the blades at desired angles to the body; a pair of handles extending upwardly,

rearwardly and outwardly from a point on the body to positions convenient to the operator; hinges serving to interconnect the handles and said body, said hinges having means permitting movement of the handles toward and from each other and toward the body; and structure releasably securing the handles in the operative position.

2. A manually operable snowplow of the character described comprising a flat central body 10 adapted to be disposed in a vertical plane when in the operative position; an outwardly and rearwardly extending blade hingedly joined to each side respectively of the body adjacent to the forward end thereof; means interconnecting each 15 blade and the body at selected points along the length thereof adjacent to the other end of the body for holding the blades at desired angles to the body; a pair of handles extending upwardly, rearwardly and outwardly from a point on the 20 body to positions convenient to the operator; hinges serving to interconnect the handles and said body, said hinges having means permitting movement of the handles toward and from each other and toward the body; and structure 25 releasably securing the handles in the operative position, said structure comprising a tie-rod between the handles at the uppermost portions thereof, one end of said tie-rod being swingably secured to one of the handles, the other end of 30 said tie-rod being releasably attached to the other handle whereby upon releasing the tie-rod the handles may be moved together.

3. A manually operable snowplow of the character described comprising a flat central body 35 adapted to be disposed in a vertical plane when in the operative position; an outwardly and rearwardly extending blade hingedly joined to each side respectively of the body adjacent to the forward end thereof; means interconnecting each 40 blade and the body at selected points along the length thereof adjacent to the other end of the body for holding the blades at desired angles to the body; a pair of handles extending upwardly, rearwardly and outwardly from a point on the 45 body to positions convenient to the operator; hinges serving to interconnect the handles and said body, said hinges having means permitting movement of the handles toward and from each other and toward the body; and structure 50 releasably securing the handles in the operative position, said structure comprising a tie-rod between the handles at the uppermost portions thereof, one end of said tie-rod being swingably secured to one of the handles, the other end of 55 said tie-rod being releasably attached to the other handle whereby upon releasing the tie-rod the handles may be moved together, said body having a tongue thereon formed to receive the tie-rod thereunder when the handles are in juxtaposition 60 and adjacent to the body after movement toward each other and toward the body about the hinges.

4. A manually operable snowplow of the character described comprising a flat central body adapted to be disposed in a vertical plane when 65 in the operative position; and outwardly and rearwardly extending blade hingedly joined to each side respectively of the body adjacent to the forward end thereof; means interconnecting each blade and the body at selected points along the length thereof adjacent to the other end of the body for holding the blades at desired angles to the body; a pair of handles extending upwardly, rearwardly and outwardly from a point on the 70 body to positions convenient to the operator; 75

hinges serving to interconnect the handles and said body, said hinges having means permitting movement of the handles toward and from each other and toward the body; and structure releasably securing the handles in the operative position, said structure comprising a tie-rod between the handles at the uppermost portions thereof, one end of said tie-rod being swingably secured to one of the handles, the other end of said tie-rod being releasably attached to the other handle whereby upon releasing the tie-rod the handles may be moved together, said body having a tongue thereon formed to receive the tie-rod thereunder when the handles are in juxtaposition and adjacent to the body after movement toward each other and toward the body about the hinges, said handles each having a collapsible support extending to the body and adapted to be folded when the handles move toward the body.

5. A manually operable snowplow of the character described comprising a flat central body adapted to be disposed in a vertical plane when

in the operative position; an outwardly and rearwardly extending blade hingedly joined to each side respectively of the body adjacent to the forward end thereof; means interconnecting each blade and the body at selected points along the length thereof adjacent to the other end of the body for holding the blades at desired angles to the body; a pair of handles extending upwardly, rearwardly and outwardly from a point on the body to positions convenient to the operator; 10 hinges serving to interconnect the handles and said body, said hinges having means permitting movement of the handles toward and from each other and toward the body; and structure releasably securing the handles in the operative 15 position, each of said means interconnecting the blades and the body comprising a brace hingedly attached at one end to the blade, a perforated fixture on the body and means for attaching the other end of the brace to the fixture at a selected 20 one of the perforations.
